UNITED STATES PATENT OFFICE.

JOHN W. HONKA, OF NEGAUNEE, MICHIGAN.

SOUND BOX FOR PHONOGRAHS.

1,404,769.

Specification of Letters Patent. Patented Jan. 31, 1922.

Application filed January 21, 1921. Serial No. 439,009.

To all whom it may concern:

Be it known that I, JOHN W. HONKA, a citizen of the United States, residing at Negaunee, in the county of Marquette and State of Michigan, have invented certain new and useful Improvements in Sound Boxes for Phonographs, of which the following is a specification.

This invention relates to sound boxes for phonographs and the like and has for its primary object to provide a simple and inexpensive construction which will produce a more natural and perfect tone in the sound reproduction.

Another object of the invention is to provide a sound box construction in which the vibrations of the stylus are communicated to the edge of the vibratory disk or diaphragm rather than to the center as has been customary heretofore.

Further objects of the invention are to provide a vibratory disk of varying thickness, to eliminate metallic sounds, to permit the mounting of the stylus directly upon the vibratory disk, to permit adjustment of the strength of the tone produced by the sound box, to procure greater flexibility and freedom of vibration in the vibratory disk, and to provide an improved connection between the stylus holder and the sound box or diaphragm.

The many other objects and advantages of my invention will be better understood by reference to the following specification when considered in connection with the accompanying drawing illustrating certain selected embodiments thereof, in which:—

Fig. 1 is a plan view of my invention complete;

Fig. 2 is a side elevation showing the sound box in the proper position for lateral groove records;

Fig. 3 is a central vertical section of the sound box in the position of Fig. 2;

Fig. 4 is a rear elevation of the sound box in the position for hill and dale records;

Figs. 5, 6 and 7 are modified forms of my invention.

Referring to the drawing, my invention is shown to comprise a sound box 10 provided with a vibratory disk or diaphragm 11 and stylus holder 12. The sound box 10 may be connected to the tone-arm 13 in any

suitable manner for the construction of the tone-arm forms no part of the present invention. This sound box is constructed preferably of wood and consists of a base 14 on which is formed an annular flange 15. The vibratory disk 11 is secured upon this annular flange along a portion of its edge by screws 16 or other suitable means. A thin strip 18 of leather, rubber or other suitable material is placed between the fixed edge portion of the disk and the opposing edge of the annular flange to maintain the disk in spaced relation therewith. A metallic strip 19 may be placed over the edge portion of the disk which is to be secured to the sound box in order to reinforce this edge. A strip 20 similar to the strip 18 should preferably be placed between the metallic strip 19 and the disk to prevent metallic contact with the disk. The forward edge portion 21 of the disk 11 is free to vibrate and the stylus holder 22 is secured to this edge.

The vibratory disk 11 is preferably made of varying thickness, the portion 21 adjacent to the stylus connection and the fixed edge being thicker than the portion 23 in order to provide the desired firmness and to secure the most perfect tone.

The stylus holder consists of an upper member 24 which is secured to the underside of the disk 11 by the fastener 25, and a lower member 26 which grips the stylus in the usual manner. The members 24 and 26 are connected by a flat spring 27 which has its opposite ends firmly secured in these members. This spring permits the lower member 26 of the stylus holder to swing laterally when the sound box is in the position shown in Figs. 2 and 3, and to move in a vertical plane when the sound box is positioned for hill and dale records, as shown in Fig. 4. Such a flat spring connection is applicable to substantially all forms of sound boxes and stylus holders.

The strength of the tone produced by the sound box is dependent upon the relative extent of the free and fixed edge portions of the disk. Where a strong tone is required, the fixed edge portion of the disk should be comparatively short to permit the maximum freedom of vibration of the disk. The vibrations are preferably transmitted by the

stylus holder to the free edge of the disk. The disk may be round, square, or of any other suitable shape.

By making the disk of wood in the manner described, the sound produced has the mellowness of a violin as distinguished from the more metallic tone of a banjo.

In the modified form of the invention shown in Figs. 5 and 6, the stylus holder 28 is supported by oppositely disposed lugs 29 on the periphery of the sound box instead of being directly connected to the vibratory disk. An arm 30 has its lower extremity secured to the stylus holder and its upper extremity is connected to the free edge portion of the vibratory disk 31. The arm 30 is pivotally mounted in the lugs 29 at 32.

In the modification shown in Fig. 7 of the drawing, a metal protecting casing 33 fits about the periphery of the sound box to form a protection therefor and the upper edge 34 of this casing is crimped inwardly over the face of the vibratory disk 35 but should be sufficiently spaced from the upper face thereof to permit freedom of action of the disk. When such a protecting casing is used, the vibratory disk 35 may be made of slightly less diameter than the sound box in order that the disk may not contact with the metal casing. The stylus holder 36 projects through a perforation 37 in the casing 33.

While I have found that better tone is produced by the use of a wooden sound box and vibratory disk, either or both of these parts may be made of any other suitable material and the advantageous features of my invention are applicable thereto. I am likewise aware that other changes in the form and arrangement of parts may be made without departing from the spirit of my invention, and I reserve the right to make all such as fairly fall within the scope of the following claims.

I claim:

- 45 1. A sound box provided with a diaphragm secured along a portion of its edge to said sound box with the remaining portion of its edge free to vibrate relative to said sound box.
- 50 2. A sound box provided with a vibratory plate secured along a portion of its edge to said sound box with the remaining portion of its edge spaced from said sound box and free to vibrate relative thereto.
- 55 3. A sound box provided with a vibratory disk secured along a portion of its edge to said sound box with the remaining portion of its edge spaced from said sound box and free to vibrate relative thereto, and a stylus holder connected to the free edge of said disk.
- 60 4. A sound box comprising a casing having a base provided with an annular flange thereon, and a diaphragm having a portion

of its edge secured to said flange and the remaining portion of its edge free to vibrate relative to said casing.

5. A sound box comprising a casing having a base provided with an annular flange, a diaphragm attached along a portion of its edge to the edge of said flange with the remaining edge portion of said diaphragm free to vibrate relative thereto, a spacing strip interposed between the attached edge portion of said diaphragm and said flange, and a stylus holder connected to said diaphragm.

6. A sound box comprising a casing open at one end, a diaphragm fitting over the open end of said casing, a binding strip on the face of said diaphragm extending along a portion of its edge and leaving the remainder of said edge free to vibrate, and diaphragm fastening means passing through said strip and said diaphragm to secure said diaphragm to said casing.

7. A sound box comprising a casing provided with an open face, a diaphragm forming a closure for said face, a spacing strip interposed between said diaphragm and said casing along a portion of the edge of said diaphragm, and fasteners passing through said diaphragm and said strip to secure said diaphragm to said casing.

8. A sound box comprising a casing provided with an open face, a diaphragm forming a closure for said face, a binding strip on the face of said diaphragm, a segmental spacing strip interposed between said diaphragm and said casing, and fasteners passing through said binding strip, said diaphragm and said spacing strip and engaging said casing to secure said diaphragm to said casing.

9. A sound box comprising a casing provided with an open face, a diaphragm forming a closure for said face, a metallic binding strip on the face of said diaphragm, an insulating strip between said binding strip and said diaphragm, a spacing strip interposed between said diaphragm and said casing, and fasteners passing through said binding strip, said insulating strip, said diaphragm and said spacing strip and engaging said casing to secure said diaphragm to said casing.

10. A sound box comprising a casing, a diaphragm supported by said casing and having a relatively thin central portion and a relatively thick rim portion, and a stylus holder connected to the rim of said diaphragm.

11. A sound box comprising a casing provided with an open face, a diaphragm forming a closure for said face, a segmental spacing strip interposed between said diaphragm and said casing, and means for securing said diaphragm upon said casing.

JOHN W. HONKA.
